UNITED STATES PATENT OFFICE.

WARREN M. BRINKERHOFF, OF AUBURN, NEW YORK.

LACE-FASTENER.

SPECIFICATION forming part of Letters Patent No. 363,276, dated May 17, 1887.

Application filed March 2, 1887. Serial No. 229,468. (No model.)

To all whom it may concern:

Be it known that I, WARREN M. BRINKERHOFF, a citizen of the United States, residing at Auburn, in the county of Cayuga and State 5 of New York, have invented certain new and useful Improvements in Lace-Fasteners; and I do hereby declare the following to be a full, clear, and exact description of the invention, such as will enable others skilled in the art to 10 to which it appertains to make and use the same.

My invention relates to lace-fasteners, and is designed to hold the laces used in shoes, gloves, or corsets, and which, when made of a proper size, may serve as a bag-fastener, a fastener 15 for horse-blankets, and in any place where it is desired to hold one or more laces or strings.

In the accompanying drawings I have shown several modes in which I have contemplated applying my invention, and have set the said 20 invention fully forth in the following specification and claims.

In the drawings, Figure 1 is a top view of the plate formed of a helical spring-coil, which constitutes one of the main features of my invention. Figs. 2 and 3 are top or plan views of different forms of my completed fastener. Fig. 4 is a cross section of the device shown in Fig. 1. Fig. 5 is a section of the device shown in Fig. 2. Fig. 6 is a section of the 30 construction shown in Fig. 3 with means of attachment removed. Fig. 7 is a sectional view taken on line $x-x$ of Fig. 3. Fig. 8 is a side view of an uncompleted plate of another form. Fig. 9 is a side view of a completed fastener, in which the form of spring shown in Fig. 8 is employed. Figs. 10, 11, 12, 13, 14, 35 15, 16, 17, and 18 are sectional views of modified forms of construction. Fig. 19 is a view of a part of a shoe with my lace-fastener attached.

In my invention I employ two plates, one of which is composed of a helix, and such plates are applied to the article in the desired position to receive the lace in such manner 45 that the lace, when drawn between the plates, is acted upon by the elastic force of the helix and securely held.

In some instances I make the spring in the form of a flat plate, as shown in Figs. 1, 4, 5, 10, 50 15, and 16. This may be attached to the article direct by turning the inner end of the hel-

ix downward to form a rivet, or by a central rivet or eyelet, as shown in Figs. 15 and 16, or other mode of attachment.

I prefer to place between the plate or helix 55 A and the article a shield, B; but it may be attached without this shield whenever it may be found desirable to do so. This shield may be made of metal or any other material possessing a sufficient degree of rigidity to protect the article beneath the helix from wear and to secure the proper compression of the lace or string by the helix.

Where the lace employed is only of moderate size, the plate or helix may be brought 60 down close against the article or the intervening shield, as shown in Figs. 5, 9, 11, 13, 15, and 16; but where a larger lace is employed, the plate or helix may, when deemed expedient, be fastened over the shield at a short distance therefrom, as shown in Fig. 10. In this figure the plate or helix A is shown separated from the shield B by a separating plate or washer, d.

In Fig. 11, instead of making the plate in the 75 form of a disk, with the coils all in one plane, I have shown the same of a curved concave form to facilitate the introduction of the lace. The same result may be accomplished in most cases by raising the outer coil of the helix a 80 little above the plane of the other coils.

In most cases where the lace to be held is exposed to great strain, I prefer to make the plate by first forming a helix of conical form, as shown in Fig. 8, and then in attaching the 85 same to the article to which it is to be applied to compress the coils to almost one plane, as shown in Fig. 9 in side elevation, and in Fig. 18 in section. I take care to construct the helix of a greater width than altitude, or so that, 90 however attached to the article with which it is to be used, each coil will lie partly in the plane of the next adjacent coil. With this construction it is impossible to force the lower coils against the central attaching connection 95 which would destroy the fastener. This feature of construction enables me to employ a greater variety of materials for making my device than would otherwise be the case, and prevents the lace being drawn between the 100 coils of the helix. This would be likely to occur if the helix were made of greater height,

with a space between the coils of the same. My construction gives a flat or slightly convex surface, bringing the coils in such close relation that it is impossible to get the lace between them. A lace drawn hastily against the upper surface of a convex fastener would slip over the same almost as easily as it would over a solid convex plate.

In Fig. 15 I have shown a construction with a plate, *b*, intervening between the plate or helix *A* and the shield *B*. This form of my fastener I have found to give good results, and by giving the plate *b* an upwardly-turned edge the lace is very easily introduced into the fastener, and with little friction upon it. In Fig. 16 I have shown another construction in which I employ a restraining or limiting plate, *c*, which adds its resistance to the movement of the outer portion of spring plate or helix when the latter is raised.

In Figs. 3, 6, 7, 12, 14, and 17 I have shown modifications, in which a second helix, *A'*, is substituted for the shield *B*. The two helices are held a distance apart, as in Figs. 6 and 7, or come in contact, as in Figs. 12, 14, and 17. In the form shown in Figs. 3, 6, and 7 the two helices are formed from one continuous piece of metal. It is not necessary that the two helices when constructed in this way should be a distance apart. They may instead be made to come close together, as in Fig. 17.

In Fig. 12 the two helices are made to form two concave plates and have their concave faces toward each other. In Fig. 14 but one of the plates or helices is of concave form, the construction resembling that shown in Fig. 13, the fastener having the helix *A'* instead of the shield *B*. In Fig. 17 the two plates or helices are flat and are brought in close contact.

The construction shown in Figs. 6 and 7 is preferably attached in the manner shown; but any other mode of attachment may be adopted.

In place of the eyelet-fastening employed in the forms shown in Figs. 12, 14, and 17, the inner end of the coil may be made to serve as a means of attachment; or a plain rivet and washer may be employed.

In Fig. 19 I have shown another form, in which two plates or helices are employed, the coils of the one resting between the coils of the opposing helix. In this construction it is preferable to give one of the plates or helices a slightly dishing form and place the convex face against the other, or to have the outer coil of one of the helices out of the plane of the other coils, so as to admit the ready insertion of the lace.

The fastener is attached to the article in the position desired, and after the lace or string to be fastened has been drawn as tight as required it is drawn under the plate or helix and wound a little more than once around the

central attaching means, causing a crossing of the lace beneath the helix, in which position it will be held against all draft or strain upon it.

The helix forms the most desirable form of plate for the purpose of a fastener. The length of the coiled material being so great and the helix being secured at the center, the outer coil readily yields to permit the introduction of the lace, so that a quite strong spring material can be employed.

It will also be observed that the lace is not only pressed by the outer coil of the helix; but in most of the forms of construction, as the cord at the point of intersection or crossing is also strongly compressed, a very firm holding of the lace is secured.

It will be understood that the plates may be made of different sizes and of different-sized material to adapt it to the particular work for which it is intended.

What I claim, and desire to secure by Letters Patent, is—

1. The herein-described lace-fastener, consisting of two plates held in close proximity to each other, one of said plates being composed of a helix, substantially as and for the purpose set forth.

2. The herein-described lace-fastener, composed of two plates or disks and a central attaching construction, one of said plates consisting of a metallic helix, substantially as described.

3. The herein-described lace-fastener, consisting of a metallic helix having a greater width than height, a shield below the helix, and a central attaching construction, substantially as described.

4. The herein-described lace-fastener, consisting of a metallic helix having a greater width than height, a shield below the helix, and the described restraining device above the helix, substantially as described.

5. The combination, with an article provided with a lace or string for the purpose of securing the edges of the same in close relation, of the herein-described lace-fastener, consisting of a metallic helix and a central attaching connection, substantially as described.

6. The combination, with an article provided with a lace or string for the purpose of securing the edges of the same in close relation, of the herein-described lace-fastener, consisting of two plates held in close proximity to each other, one of said plates being composed of a helix, substantially as and for the purpose set forth.

In testimony whereof I affix my signature in presence of two witnesses.

WARREN M. BRINKERHOFF.
